UNITED STATES PATENT OFFICE.

PHILIP H. DU BOIS, OF WATERLOO, NEBRASKA.

HAME ATTACHMENT.

SPECIFICATION forming part of Letters Patent No. 729,742, dated June 2, 1903.

Application filed June 24, 1901. Serial No. 65,849. (No model.)

To all whom it may concern:

Be it known that I, PHILIP H. DU BOIS, a citizen of the United States, residing at Waterloo, in the county of Douglas and State of Nebraska, have invented a new and useful Hame Attachment, of which the following is a specification.

The invention relates to improvements in hame attachments.

10 The object of the present invention is to provide a simple and comparatively inexpensive attachment for hames designed to dispense with the use of an ordinary horse-collar and adapted to be readily applied to hames of the ordinary construction and capable of adjustment to adapt the hames to the neck of the animal to which they are applied.

15 The invention consists in the construction and novel combination and arrangement of parts hereinafter fully described, illustrated in the accompanying drawings, and pointed out in the claim hereto appended.

20 In the drawings, Figure 1 is a perspective view of a pair of hames constructed in accordance with this invention. Fig. 2 is a rear elevation of the same. Fig. 3 is a horizontal sectional view illustrating the manner of securing the side pads to the hames. Fig. 4 is a detail view illustrating the construction of 25 the adjustable connection to which the top pad is pivoted. Figs. 5 and 6 are detail views of the hame-fastener.

25 Like numerals of reference designate corresponding parts in all the figures of the drawings.

30 11 designate side pads provided with upper and lower straps 2 and 3 and arranged at the inner and rear faces of a pair of hames 4 and adapted to fit against the shoulders of 35 a horse or other animal to take the place of an ordinary horse-collar. The upper and lower straps, which are provided with suitable buckles, encircle the hames and secure the pads to the same, and the said pads may 40 be constructed of any suitable material, as will be readily understood. The hames are 45 detachably secured together at their lower ends by a hame-fastener 5, and they are secured near their upper ends by straps 6 to an 50 adjustable connecting device composed of two approximately L-shaped sections 7, having upright arms 8 and approximately hori-

zontal arms 9. The upright arms 8 are provided at opposite sides with flanges 10, receiving the upper portions of the hames and 55 having slots 11, through which pass the straps 6, which secure the sections 7 to the hames. The upper arms 9 are provided with side flanges 12, having perforations 13, adapted to receive a transverse fastening device 14, 60 whereby the sections are adjustably connected. The arm of one section fits between the flanges of the arm of the other section, and the transverse hame-strap 15, which connects the upper ends of the hames, is received between the side flanges 12 and is held by the same out of contact with a top pad 16, which is pivotally connected to the lower ends of the upright arms 8 of the sections 7. By adjusting the upper arms of the sections on 65 each other the distance between the hames may be increased and diminished and the said hames may be readily arranged to fit animals of different sizes.

70 The top pad 16, which is arched, is connected at its ends to the arms 8 by rivets 17 or other suitable pivots, and it is adapted to rest upon the neck of an animal, and the pivotal movement will permit the hames to yield to horse motion without causing the top pad 75 to rub the neck of the animal.

75 The hame-fastener, which is adapted to be used on different portions of a harness for a snap-hook, consists of a hook 18, having a shank 19 and a spring-actuated plate 20, 80 mounted on the shank and adapted to close the mouth of the hook. The shank is recessed to receive a spring 21, which is retained in the recess by a plate 22 and by the said plate 20, which is slotted, as indicated in Fig. 85 6. The stationary plate 22 is secured to the shank of the hook by fastening devices 23, which also fasten a metal strap 24 to the device. The movable plate is provided with a transverse portion 25, located between its 90 ends and engaged by the coiled spring 21, which holds the outer end of the slide normally in contact with the bill of the hook. The metal strap is doubled or bent at its center to form two sides and to provide a bend or loop 95 which is linked into the loop at the lower end of one of the hames, and the hook 18 engages the loop of the other hame. The strap 24 may also be supported by a transverse piece 100

26, arranged as clearly shown in Fig. 5 of the accompanying drawings.

It will be seen that the hame attachment is simple and comparatively inexpensive in construction, that it is adapted to take the place of an ordinary horse-collar, and that the pivotally-mounted top pad will prevent the neck of a horse or other animal from becoming chafed.

10 What I claim is—

The combination with a pair of hames, of an attachment comprising a pair of laterally-flanged hame-engaging plates provided at their upper ends with vertically-flanged extensions, adjustably nested together and pro-

vided with alining perforations, a flexible pad pivotally connected with the lower inner ends of the hame-engaging plates, straps connecting the upper ends of the hames and resting between the nested flanges, and a connecting-pin engaging the alining perforations in said flanges above the connecting-straps and securing the latter against displacement.

In testimony that I claim the foregoing as my own I have hereto affixed my signature in the presence of two witnesses.

PHILIP H. DU BOIS.
